(57) **CLAIM**

The ornamental design for a die plate assembly for probe head, as shown and described.

DESCRIPTION

FIG. 1 is a perspective view of a die plate assembly for probe head, showing the upper die plate and lower die plate in an assembled position according to our design;

FIG. 2 is a front view thereof, showing the upper die plate and lower die plate in an assembled position, the rear side, the left side and the right side being an identical image;

FIG. 3 is a top plan view thereof;

FIG. 4 is a bottom plan view thereof;

FIG. 5 is an enlarged sectional view taken along line 5-5 of FIG. 3, showing the upper die plate and lower die plate of the die plate assembly for probe head in an assembled position;

FIG. 6 is an enlarged sectional view taken along line 6-6 of FIG. 3, showing the upper die plate and lower die plate of the die plate assembly for probe head in an assembled position;

FIG. 7 is a top perspective view of the upper die plate of the die plate assembly for probe head;

FIG. 8 is a front view of the upper die plate of the die plate assembly for probe head, the rear side being an identical image;

FIG. 9 is a left side elevational view of the upper die plate of the die plate assembly for probe head, the right side being an identical image;

FIG. 10 is a top plan view of the upper die plate of the die plate assembly for probe head;

FIG. 11 is a bottom plan view of the upper die plate of the die plate assembly for probe head;

FIG. 12 is a bottom perspective view of the upper die plate of the die plate assembly for probe head;

FIG. 13 is a top perspective view of the lower die plate of the die plate assembly for probe head;

FIG. 14 is a front view of the lower die plate of the die plate assembly for probe head, the rear side, the left side and the right side being an identical image;

(Continued)

6

FIG. 15 is a top plan view of the lower die plate of the die plate assembly for probe head;

FIG. 16 is a bottom plan view of the lower die plate of the die plate assembly for probe head; and,

FIG. 17 is a bottom perspective view of the lower die plate of the die plate assembly for probe head.

The broken lines depict portions of the die assembly and form no part of the claimed design.
